(57) **CLAIM**

The ornamental design for an upholstered furniture panel as shown and described.

DESCRIPTION

FIG. 1 is a front perspective view of the upholstered furniture panel;

FIG. 2 is a front view thereof;

FIG. 3 is a rear view thereof;

FIG. 4 is a top view thereof;

FIG. 5 is a bottom view thereof;

FIG. 6 is a side view thereof;

FIG. 7 is an opposite side view thereof;

FIG. 8 is a front perspective view of the upholstered furniture panel incorporated into an exemplary furniture product; and,

FIG. 9 is a side perspective view of the upholstered furniture panel.

The broken lines shown in the drawings illustrate portions of the upholstered furniture panel that form no part of the claimed design. The additional broken lines in FIG. 8 illustrate an exemplary environment in which the upholstered furniture panel may be used and form no part of the claimed design.

1 Claim, 5 Drawing Sheets
